UNITED STATES PATENT OFFICE.

JOAH BROGDEN, OF MELROSE PARK, PENNSYLVANIA, ASSIGNOR TO DAVID LUPTON'S SONS COMPANY, OF PHILADELPHIA, PENNSYLVANIA, A CORPORATION OF PENNSYLVANIA.

MILL FURNITURE.

Application filed February 17, 1923. Serial No. 619,568.

To all whom it may concern:

Be it known that I, JOAH BROGDEN, a citizen of the United States, residing at Melrose Park, county of Montgomery, and State of Pennsylvania, have invented certain new and useful Improvements in Mill Furniture, of which the following is a specification, reference being had to the accompanying drawings.

10 This invention relates to mill furniture and more particularly to fixtures designed especially for hosiery mills.

An object of the invention is to provide mill furniture which is constructed with a view to decreasing the weight of such equipment by the substitution of sheet metal for wood, as heretofore employed; to eliminate the hazard of fire; to prevent the propagation of vermin, and in general to ensure the 20 durability and longevity of equipment of this nature.

The several kinds of fixtures herein described while adhering to one general type and differing only in details are uniformly 25 characterized by the provision of one or more compartments, one of which is utilized as an enclosure for power transmission mechanism, for driving a machine, such as a seaming or looping machine for finishing 30 hosiery, which is supported upon the top surface of the article, the other compartments being employed for the temporary storage of finished work or the collection of waste material.

35 In the accompanying drawings forming a part of this application Figure I is a view in perspective of a bank of unit articles of mill furniture constructed in accordance with my invention showing the appearance thereof in 40 assembled relation.

Figure II is a view in perspective of a fixture of the table type constructed entirely of sheet metal, in accordance with the present invention, and fashioned so as to be available 45 for use as a seaming table.

Figure III is a view in vertical section taken on the line III-III of the preceding figure.

50 Figure IV is a view in elevation of the rear side of the table.

Figure V is a view in perspective of an article of furniture of the table type, constructed of sheet metal in accordance with my invention and illustrating a modified

construction available for use as a looping 55 table.

Figures VI and VII are views in vertical section taken on the lines VI-VI and VII-VII respectively of Figure V.

Figure VIII is a view in rear elevation of 60 the looping table; and

Figure IX is a detail sectional view illustrating a slight modification of the furniture top for accommodation of sewing or seaming machines of the flush bed plate 65 type.

With reference to Figures I, II, III and IV the construction shown therein comprises the pedestals 10 and 11 formed of panels of sheet steel or other suitable and durable 70 metal or alloy, connected at their upper ends by means of the top section 12 in any suitable manner as by bolting, riveting, welding, etc. The front and rear edges of the top section 12 are bent downwardly as at 75 13 and 14 respectively to increase the rigidity of the structure and to simulate thickness of the top section. The vertical edges of the pedestal panels 10, 11 may likewise be bent laterally to add rigidity. The space between 80 the end pedestals 10, 11 is divided by means of a transverse partition 15 of sheet metal, said partition being bent laterally at the front of the table and extended toward the left hand pedestal 10 and secured thereto at 85 its edges and to the edge of the top section to form the front 16 of a storage compartment 17. The bottom 18 of the compartment 17 is formed of a panel of sheet metal which is extended toward the rear side of 90 the unit article and secured in any suitable manner to the lower edge of a rear panel 19 which extends the width of said article, or it is supported upon the end pedestal 10 and spaced from the lower ends of the pedestals 95 10, 11, and from the top section 12, in the latter instance to provide openings through which finished work may be withdrawn.

The rear edge of the partition 15 may be bent laterally to form a mullion 20 cooperating with doors to be hereafter described. A panel 21 is extended downwardly at an incline from the edge 13 of the top section and bent horizontally to form the bottom 22 of a compartment 23, the rear edge of the 105 bottom section 22 being supported upon the lower edge of the aforesaid panel 19. The compartments 17 and 23 are closed through

the medium of doors 24 and 25 respectively, constructed of sheet metal and having their lower edges hinged to the panel 19 with their adjacent edges lapping the mullion 20 and their upper edges provided with locking devices 26 cooperating with keeper members mounted on the edge 14 of the top section 12 to retain said doors in closed position.

10 While the articles of furniture described may be employed singly it is preferable to align them in banks of six, more or less, so that the machines supported thereon may be operated conveniently from a single counter shaft the latter being indicated in the drawings at 27 as extending horizontally through the several pedestals 10, 11. Such an arrangement is illustrated in Figure I of the drawings. Within the compartment 23 a 15 driving pulley 28 may be located and mounted upon the shaft for operating the machine; and if desired an intermediate pulley couple 29 may be located in said compartment for transmitting the speed to a rate 20 suitable for operating a machine, indicated by dotted lines and designated 30. The unit article described is particularly suited as a seaming table, and the dotted line indication represents the outline of a seaming machine 25 for stitching the seams of hosiery.

By reason of the inclined panel 21 the operator is permitted, while seated, to closely approach the table edge so as to conveniently manipulate the machine; the 30 work, which is usually withdrawn from a receptacle from the side of the operator, after having been finished by the performance thereon of the operation afforded by the seaming machine is dropped into an 35 opening 31 in the top section of the table for temporary storage in the compartment 17, from which it is subsequently removed by an operator to whom the duty is assigned, and positioned at the opposite or 40 rear side of the table, the door 24 being lowered for this purpose. In this manner the work is retained in a closed compartment and protected against the possibility of soiling.

45 I have illustrated in Figures V, VI, VII and VIII a modified construction of an article of furniture of the table type more suitable for use as a looping table because of the characteristics of a looping machine which 50 must be accommodated. The construction comprises in detail end pedestals 32 formed of panels of sheet metal, narrower in width than those embodied in the form of table described above but in a similar manner embodying a top section 33 reinforced at its front and rear edges by the downward deflection of the metal at 34 and 35 respectively, also simulating thickness for the 55 more ornamental appearance of the table.

60 This type of table is characterized by an in-

clined panel section 36 extending from a lower point adjacent the forward side of the table and extending upwardly at an incline beyond the plane of the rear edges of the pedestal and then bent downwardly as at 37 70 to simulate thickness and add rigidity.

The panel 36 extends from end to end of the table, and at one end is extended upwardly by the provision of a panel section 38 forming a chute and having an integral 75 end wall 39 which is secured to the left hand pedestal 32. The space between the inclined panel 36 and the top section 33 is divided by means of a transverse partition 40 having its rear edge bent laterally and extended 80 toward the right hand pedestal 32 and secured thereto to form the front wall 41 of a compartment 42 for the reception of the power transmission mechanism.

The rear edge of the panel section 36 is 85 extended downwardly and its edge bent to provide reinforcement; and hingedly mounted on said downturned portion are one or more doors 43 provided with locking 90 devices 44 at their upper edges for cooperation with keepers carried by the rear edge 35 of the top section to form closures for the compartment 42 and a compartment 45 defined by the left hand pedestal and the 95 partition 40.

A storage compartment or receptacle is provided at the lower portion of the table in the form of front and rear panels 46 and 47 respectively, connected by the bottom 100 panel 48, the upper edges of said panels 46 and 47 being spaced from the inclined bottom 36 to permit the introduction of articles at the front side of the table and the withdrawal thereof at the rear side.

A door 49 is hingedly mounted upon the panel 47 to swing in a vertical plane, and is provided with a locking device 50 for cooperation with a keeper carried by the downward extension of the inclined bottom 36. A panel section 51 is extended downwardly from the inclined bottom 36 in a plane coinciding with the plane of the rear edges of the pedestals to a point in horizontal alignment with the rear end of the inclined bottom 36 to accommodate therebeneath a sliding drawer 52 which may be mounted in any manner found suitable or convenient.

115 As in the form first described this type of table may be used singly but preferably in banks of six, more or less, so that the counter shaft 53 may be extended through said tables for the purpose of supplying power to the machines supported thereon through the medium of pulleys 54 having belt connections to the machines.

120 This table is designed particularly for supporting a looping machine for knitted material, which machines are characterized 125 by a horizontal wheel 55 shown in dotted 130

lines as suspended from a supporting bracket 56 so as to extend beyond the rear edge of the table top with the periphery of the wheel disposed above the chute 38. This arrangement is made in view of the fact that during the operation of the looper a waste product is formed termed ravellings which readily drop upon the chute 38 and are conveyed by gravity to the lower end 10 of the compartment 45 for collection therein. The finished work is dropped into the lower receptacle from which it is subsequently removed by the operator positioned at the rear side to the table as the 15 door 49 is lowered for that purpose.

In instances where my improved furniture is to be used for mounting of sewing or seaming machines of the flush bed plate type, I provide in the top 12, openings 20 60 Figure IX, preferably inwardly flanged as indicated at 61, and of a size appropriate to accommodate the casing 62 in which the actuating mechanism of the machines is housed. Such machines may be readily anchored by 25 bolting or otherwise securing the marginal portions of their bed plates 63 directly to the table top.

The installation of the equipment described in a mill is conducive to maintaining a neat and orderly appearance of the mill and aids in establishing a systematic arrangement for the handling of the finished and unfinished work. The mill floor is clean at all times and free of the accumulation of 35 work which is an incident in the use of old wooden equipment of hosiery mills. The driving belts and shafting are all enclosed, thereby protecting the operator against injury. By adapting the structure of the table to the particular kind of machine it is designed to support, a maximum efficiency in the work of the machine and operator is obtained.

It will be apparent from the foregoing 45 that the principles of construction described may be employed in the development of any type of equipment found necessary to meet the requirements of different industries, and hence I do not wish to be limited to the 50 exact construction of any of the forms shown but solely by such limitations as are included in the appended claims.

Having thus described my invention, I claim:

1. A supporting unit for aligned power 55 driven machines, each machine being connected with a power shaft running the full length of the unit and beneath the same, said shaft being connected to each machine, with the connections enclosed in individual 60 compartments, adjacent compartments in the unit for the reception of goods, an opening in the top of the supporting unit for each of the latter compartments, said openings being to one side of each machine, and other 65 openings at the back of the unit affording access to each of the compartments.

2. A supporting unit—constructed entirely of sheet metal—for aligned power driven machines, each machine being connected with a power shaft running the full length of the unit and beneath the same, said shaft being connected to each machine, with the several connections enclosed in individual compartments, adjacent compartments 70 in the unit for the reception of goods, an opening in the top of the supporting unit for each of the latter compartments, said openings being aligned to one side of each machine, and other openings at the 75 back of the unit affording access to each of the compartments for the removal of work.

3. A sheet-metal supporting unit for aligned power driven machines, each machine being connected with a power shaft 85 running the full length of the unit and beneath the same, said shaft being connected to each machine, with the connections enclosed in individual compartments, adjacent compartments 90 in the unit for the reception of goods, aligned openings in the top of the supporting unit affording individual access into the latter compartments, and other openings at the back of the unit having fall-down doors to afford access to each 95 compartment for the removal of finished work.

In testimony whereof, I have hereunto signed my name at Philadelphia, Pennsylvania, this 14th day of February, 1923.

JOAH BROGDEN.
